United States Patent

Des. 238,973

Patented Feb. 24, 1976

238,973

UTILITY BOX FOR VEHICLES

Arlyn E. Miller, 8 S. Beaver,
Boise City, Okla. 73933

Filed Oct. 29, 1973, Ser. No. 410,705

Term of patent 14 years

Int. Cl. D3—99

U.S. Cl. D87—1 R

Fig. 1

Fig. 2

Fig. 3

Fig. 4

Fig. 5

FIG. 1 is a top plan view of a utility box for vehicles showing my new design;

FIG. 2 is a front elevational view thereof;

FIG. 3 is a rear elevational view thereof;

FIG. 4 is a bottom plan view thereof; and

FIG. 5 is a left side elevational view thereof.

I claim:

The ornamental design for a utility box for vehicles, as shown.
